Brass Works, Incorporated, Chicago, Ill., a corporation of Illinois

Application December 13, 1933, Serial No. 50,054

Term of patent 3½ years

To all whom it may concern:

Be it known that I, FRANK J. LISKA, a citizen of the United States, residing at Chicago, in the county of Cook and State of Illinois, have invented a new, original, and ornamental Design for a Torchère, of which the following is a specification, reference being had to the accompanying drawing, forming a part thereof.

The figure is a perspective view of a torchère,
showing my new design.

I claim:

The ornamental design for a torchère, as shown.

FRANK J. LISKA.
